UNITED STATES PATENT OFFICE.

WALTER C. YUND, OF AMSTERDAM, NEW YORK.

POCKET FOR KNITTED GARMENTS.

Application filed October 8, 1928. Serial No. 311,188.

This invention relates to a pocket construction adapted particularly for knitted garments, such as sweaters, knit coats, and the like, and also to the method of forming such 5 pocket construction. The knitted cloth in such garments is generally thick and heavy, and more or less difficulty exists in applying pockets thereto so as to make a strong as well as a smooth and neat construction. Various 10 methods are in use for applying pockets to garments of this kind, but as a rule they are not entirely satisfactory and involve considerable handwork in applying the pocket or the parts of the pocket to the material of the garment, thus making the operation slow and expensive. Also the pockets as previously made 15 are more or less elastic around the opening thereof so that they soon sag or stretch out of shape.

20 The present invention aims to provide a simple method by which pockets may be formed in a garment of that kind and in which the mouth of the pocket or opening has no thick or bulky seams around the same and 25 which will not sag or stretch out of shape.

A further object is to provide a pocket construction in the formation of which the operations may be carried on practically entirely by machinery without the use of any 30 handwork.

A still further object is to provide a pocket construction which is neat in appearance and the opening to which is so formed as to resist pulls or strains tending to tear or draw 35 the same out of shape.

Various other objects and advantages of the invention will be apparent from the following specification taken in connection with the accompanying drawings, in which:

40 Figure 1 is a plan view illustrating the first stage in forming the new pocket construction;

Figure 2 is a vertical section on the line 2—2 of Fig. 1;

Figure 3 is a plan view illustrating a further stage in the formation of the improved 45 pocket;

Figure 4 is a vertical section on the line 4—4 of Fig. 3;

Figure 5 is a plan view illustrating a still 50 further stage in the formation of the improved pocket;

Figure 6 is a vertical sectional view on the line 6—6 of Fig. 5;

Figures 7 and 8 illustrate further stages in 55 the formation of the pocket;

Figure 9 is a plan view looking toward the

front face of the garment and illustrating a still further stage in making the pocket;

Figure 10 is a rear view illustrating the condition of the various parts at the stage illustrated in Fig. 9;

Figure 11 is a plan view of the rear face of the garment showing the appearance of the completed pocket; and

Figure 12 is an enlarged vertical sectional view substantially on the line 12—12 of Fig. 11 and showing the completed pocket construction.

Referring to the drawings in detail by means of the reference characters thereon, 10 70 indicates a portion of the garment cloth or material in which the pocket is formed, the front face or outer side of the garment cloth appearing in this view. Applied to the front face of the garment cloth 10 is an upper pocket 75 portion 11 and a lower pocket portion 12, both preferably formed of knitted or other suitable material.

As illustrated in the drawings, the pocket portions 11 and 12 are preferably made of 80 separate pieces, and first temporarily fastened to the front face of the garment cloth as by means of pins P, the lower edge of the portion 11 and the upper edge of the portion 12 being preferably flat and unfolded and arranged close to each other. The lower edge of the portion 11 and the upper edge of the portion 12 each has applied thereto a strip of 85 strong and relatively inelastic tape 11^a and 12^a respectively, this tape being secured to the 90 respective edges of the pocket portions by means of stitching 11^b and 12^b respectively. The strips of tape may be, and preferably are, sewed to the edges of the pocket portions before said portions are placed against the 95 front face of the garment. The edges of the pocket portions 11 and 12 to which the tape is applied will hereinafter be termed the "taped" edges.

After the pocket portions 11 and 12 have 100 been applied to the front face of the garment material with their taped edges adjacent each other, a line of through-and-through stitching 11^c is applied to the lower edge of the upper portion 11, and a similar line of stitching 12^c is applied to the upper edge of the lower portion 12, one of these lines of stitching extending through the tape 11^a, the underlying edge of the portion 11, and the cloth of the garment, and the other extending through the tape 12^a, the upper edge of the portion 12, 105 and the cloth of the garment. Preferably 110

the through-and-through lines of stitching 11^c and 12^c are connected at their ends by transverse lines of stitching indicated at 13 in Fig. 3. By this means the pocket portions 5 11 and 12 are secured to the front face of the garment material 10.

As the next step in the operation, the material of the garment is slit between the tapered edges of the pocket portions 11 and 12, this 10 slit, which is designated by the numeral 14, extending substantially the entire width of the pocket portions but terminating slightly short of the transverse stitching 13.

The condition of the various parts at this 15 stage of the operation is illustrated particularly in Figs. 5 and 6 which show the slit 14 slightly opened.

As the next stage in the operation, the joint 20 between the upper pocket portion 11 and the cloth of the garment and the joint between the lower pocket portion 12 and the cloth of the garment are overstitched, as illustrated at 15, in a manner well-known in the art. For this purpose the pocket portions 11 and 25 12 are turned into substantially the same plane as the plane of the cloth of the garment, and the overseaming is applied across the top and bottom and around the edges of the slit 14. This overseaming is applied for the purpose 30 of strengthening the joint between the pocket portions and the body of the garment and also for the purpose of covering up the raw edges so as to prevent any unraveling of the cloth and produce a more finished appearance. 35

Figure 7 illustrates the parts after such overseaming operation has taken place and the pocket portions 11 and 12 again turned 40 into position parallel with the cloth of the garment. In this figure the parts of the structure adjacent the slit are somewhat opened up to make the illustration more clear.

The next step in the operation consists in 45 applying a strip of strong and relatively inelastic braid to the joint between the upper pocket portion 11 and the cloth of the garment and also to the joint between the lower pocket portion 12 and the cloth of the garment. Such braid is illustrated at 16 in Figure 8 and particularly in Figure 9. This braid 16 extends around the entire slit or pocket opening, as clearly appears from Figure 9, one part of said braid extending around 55 the upper portion of the pocket opening and another part extending around the lower portion thereof. The braid 16 is secured in place by through-and-through stitching 16^a which extends through the braid, the parts of joint 60 beneath the same and also preferably through the adjacent overstitching 15.

After the various operations above described have been performed, the pocket portions 11 and 12 are forced through the slit or opening 14 to the rear side of the garment

material. To further explain, it will be noted that the pocket portions 11 and 12, up to the stage illustrated in Figure 8, are on the front or outer side of the garment cloth, and Figure 9 shows the parts after the portions 11 70 and 12 have been forced through the opening 14 to the rear side of the garment cloth. It will be seen that, when the pocket portions 11 and 12 are thus forced through the slit 14 and drawn down tightly, the upper and lower strips of braid 16 will appear on the front side of the garment cloth. In other words, Figure 9 shows the front face of the garment material 10 and with the braid 16 as it appears extending around the pocket opening. 80 Figure 10 shows the rear face of the garment at this stage with the overseaming on the upper side of the slit or pocket opening appearing therein, the overseaming on the lower side of this opening being covered by the 85 pocket portion 11.

After the pocket portions 11 and 12 have been forced through the slit or opening 15 and drawn down into position, such portions are sewed together around their edges as 90 illustrated at 17 to form the complete pocket. The complete pocket as viewed from the rear of the garment is illustrated in Figure 11.

Also Figure 12 illustrates the various parts 95 after the pocket has been finished. From this figure it will be noted that the lower pocket portion 12 has been drawn rearwardly through the pocket opening and downwardly and forms the front part of the pocket. For the sake of clearness in defining the structure, the right-hand face of the pocket portion 12 as it appears in Figure 12 will be designated as the rear face and is indicated at R in Figure 12. Also, as shown in Figure 12, the upper pocket portion 11 has 100 been drawn rearwardly and downwardly and forms the rear portion of the completed pocket. For the sake of clearness the left-hand face of the portion 11 as it appears in Figure 12 will hereafter be designated as the front face of this pocket portion and is designated by the letter F in said figure. Also in this figure it will be seen that the upper strip of braid 16 appears on the front of the garment and that the lower strip of braid 16 also 110 appears on the front of the garment just inside of the pocket. The pocket portion 12 is preferably made of such length that when drawn inwardly and downwardly, it will pull the lower portion of the braid 16 somewhat inside of the pocket opening. This 120 serves to give the pocket a neat appearance but is, of course, not absolutely essential.

It will be noted particularly from Figures 9 and 10 that the ends of the braid 16 and the ends of the tapes 11^a and 12^a are free, and in sewing the edges of the pockets together by the seaming 17, as illustrated in Figure 11, it is preferred to sew in such free ends of the braid and tapes. Also it is desirable that 130

the ends of the pocket opening be strengthened by what is generally known as "butt stitching," which is illustrated at 18 in Figure 11, such butt stitching being a through-and-through stitching which serves to further strengthen the corners or ends of the pocket.

From the foregoing, it will be seen that a pocket produced in the manner described will include a piece of strengthening tape extending across the top and bottom of the pocket opening. This serves to make the pocket opening practically inelastic so that it will not stretch out of shape. Also the braid which is applied around the pocket opening will further contribute toward this end. In fact, the braid, which is very strong and inelastic, will alone serve the purpose of greatly strengthening the pocket opening even in the absence of the tape which is embodied in the seam around the pocket opening.

Changes may obviously be made in the details of the construction heretofore described, and the various steps may be carried out in a somewhat different order than that described, and it is therefore to be understood that the invention is not limited to the precise structure disclosed nor to the precise order of steps set forth.

Having thus described the invention, what is claimed as new and desired to be secured by Letters Patent is:

1. The method of forming a pocket in a knitted garment which consists in placing flat upon the front or outer face of the garment cloth an upper or rear pocket portion and a separate lower or front pocket portion with the lower edge of said upper portion arranged in proximity to the upper edge of said lower portion, the adjacent edges of said upper and lower pocket portions each being flat and unfolded and each having a strip of strong relatively inelastic tape material extending along the same, sewing said upper and lower pocket portions to the cloth of the garment by lines of through-and-through stitching extending across the lower edge of said upper portion and the upper edge of said lower portion and through the tape material, pocket material and the garment cloth, forming a slit in said garment cloth between the adjacent edges of said pocket portions, forcing said pocket portions through said slit, and securing the edges of said portions together to form the pocket.

2. The method of forming a pocket in a knitted garment which consists in taking two separate portions of pocket forming material each having a flat unfolded edge, applying a strong relatively inelastic strip of tape material to the flat edge of each of said portions, placing said pocket portions flat against the outer or front face of the garment cloth with the taped edges thereof adjacent each other, sewing each of said pocket

forming portions to the garment material by a line of through-and-through stitches extending through said tape material, said pocket forming material and garment material, said line of stitches extending substantially parallel to the taped edges of said pocket forming portions, cutting a slit through the garment cloth between said taped edges of the pocket forming portions, forcing said pocket forming portions through said slit and securing the edges of said portions together to form the pocket.

3. The method of forming a pocket in a garment which consists in applying pocket forming material to the front face of the garment, said material comprising upper and lower pocket forming portions, applying two separated rows of stitching extending transversely of said pocket forming portions and securing the same to the garment material, cutting a slit through said garment material between said two rows of stitches, said rows of stitches being substantially parallel with said slit, sewing a strip of braid in the joint between the front face of the upper pocket forming portion and the front side of the garment material, forcing said pocket forming portions through said slit and sewing the same together at the edges to form the pocket.

4. The method of forming a pocket in a garment which consists in applying pocket forming material to the front face of the garment, said material comprising upper and lower pocket forming portions, applying two separated rows of stitching extending transversely of said pocket forming portions and securing the same to the garment material, cutting a slit through said garment material between said two rows of stitches, said rows of stitches being substantially parallel with said slit, sewing a strip of braid in the joint between the front face of the upper pocket forming portion and the front side of the garment material, sewing a strip of braid in the joint between the rear face of the bottom pocket forming portion and the front face of the garment material, forcing said pocket forming portions through said slit and sewing the same together at the edges to form the pocket.

5. The method of forming a pocket in a garment which consists in taking two separate portions of pocket forming material, applying a relatively inelastic strip of tape material to one edge of each of said portions, placing said portions against the outer or front face of the garment cloth with the taped edges thereof adjacent each other, sewing each of said pocket forming portions to the garment material by a line of through-and-through stitches extending through said tape material, said pocket forming material and garment material, said line of stitches extending substantially parallel to the taped

edges of said pocket forming portions, cutting a slit through the garment cloth between said taped edges of the pocket forming portions, sewing a strip of braid in the joint between the front face of the upper pocket forming portion and the front side of the garment material, forcing said pocket forming portions through said slit and securing the edges of said portions together to form the pocket.

6. The method of forming a pocket in a garment which consists in taking two separate portions of pocket forming material, applying a relatively inelastic strip of tape material to one edge of each of said portions, placing said portions against the outer or front face of the garment cloth with the taped edges thereof adjacent each other, sewing each of said pocket forming portions to the garment material by a line of through-and-through stitches extending through said tape material, said pocket forming material and garment material, said line of stitches extending substantially parallel to the taped edges of said pocket forming portions, cutting a slit through the garment cloth between said taped edges of the pocket forming portions, sewing a strip of braid in the joint between the front face of the upper pocket forming portion and the front side of the garment material, sewing a strip of braid in the joint between the rear face of the bottom pocket forming portion and the front face of the garment material, forcing said pocket forming portions through said slit and securing the edges of said portions together to form the pocket.

7. The herein described pocket construction for garments comprising in combination with the cloth of the garment having a slit therein, the upper and lower edges of which are turned inwardly or rearwardly, a rear pocket portion having its upper edge turned rearwardly and positioned against the in-turned upper edge of said slit and secured thereto by through-and-through stitching, a strip of relatively non-elastic braid sewed in the front side of the joint between said upper inturned edge of said slit and the upper inturned edge of said rear pocket portion, a front pocket portion having its upper edge turned forwardly and abutting the inturned lower edge of said slit, said last named edges being secured together by through-and-

through stitches, and a strip of relatively non-elastic braid secured in the joint between the rear edge of said front pocket portion and the front edge of said garment material.

8. The herein described pocket construction for garments comprising in combination with the cloth of the garment having a slit therein, the upper and lower edges of which are turned inwardly or rearwardly, a rear pocket portion having its upper edge turned rearwardly and positioned against the in-turned upper edge of said slit and secured thereto by through-and-through stitching, a strip of relatively non-elastic braid sewed in the front side of the joint between said upper inturned edge of said slit and the upper in-turned edge of said rear pocket portion, a front pocket portion having its upper edge turned forwardly and abutting the inturned lower edge of said slit, said last named edges being sewed together by through-and-through stitches.

9. The herein described pocket construction for garments, comprising in combination with the cloth of the garment having a slit therein, the upper and lower edges of which are turned inwardly, a rear pocket portion having its upper end turned inwardly and positioned against the in-turned upper edge of said slit, a re-enforcing strip positioned on the rear side of the upper edge of said rear pocket portion, through-and-through stitches securing together said strip, said in-turned upper edge of the rear pocket portion and the in-turned upper edge of the slit, a front pocket portion having its upper edge turned forwardly and abutting the in-turned lower edge of said slit, a re-enforcing strip positioned on the upper edge of said front pocket portion and on the side thereof away from the in-turned lower edge of said slit, through-and-through stitches securing together said strip, said outwardly turned upper edge of the front pocket portion and the in-turned lower edge of said slit, a strip of braid sewed into the joint between the front edge of said rear pocket portion and the front face of the garment, and a strip of braid secured in the joint between the rear face of said front pocket portion and the front face of the garment.

In testimony whereof I hereunto affix my signature.

WALTER C. YUND.
